Harry P. Henoch, INVENTOR.

BY

Geo. P. Kimmel. ATTORNEY.

UNITED STATES PATENT OFFICE.

HARRY P. HENOCHE, OF CHICAGO, ILLINOIS.

CHECK-BOOK HOLDER.

Application filed May 12, 1925. Serial No. 29,758.

To all whom it may concern:

Be it known that I, HARRY P. HENOCHE, a citizen of the United States, residing at Chicago, in the county of Cook and State 5 of Illinois, have invented certain new and useful Improvements in Check-Book Holders, of which the following is a specification.

This invention relates to a holding device and pertains particularly to a holding device 10 designed to be used in connection with a folding back for a folding pocket check book.

The primary object of this invention is the provision, in a manner as hereinafter set 15 forth, of a hold down device for use in connection with a removable back or binder for folding check books or other folding pads, to hold in position the free ends of the leaves of the pads.

20 It is well known that in the use of folding pocket check books, that when one opens the check book to use the same, the free ends of the leaves of the book insist upon swinging over to the position in which they have 25 been held while the book was in folded position. This is very annoying when one is trying to write upon the check, and to overcome this annoyance, the present device has been invented.

30 The invention will be best understood from a consideration of the following detailed description taken in connection with the accompanying drawing forming a part 35 of this specification, with the understanding that the invention is not confined to any strict conformity with the showing of the drawing but may be changed and modified so long as such changes and modifications mark no material departure from the salient 40 features of the invention as expressed in the appended claims.

In the drawing:—

Figure 1 shows a folding check book 45 opened out and secured in a back or binder, showing the device embodying this invention carried by the binder and engaging the edges of the check book.

Figure 2 is a longitudinal section through the check binder, when the same is closed, 50 and the device embodying this invention.

Figure 3 is a transverse section taken upon the line 3—3 of Figure 2.

Referring now to the drawing in detail 55 wherein like numerals of reference indicate corresponding parts throughout the several

views, there is indicated by the numeral 1 a binder of the type usually supplied gratis as advertisement by banks and other business houses, for holding and protecting bank books or other folding pads. This binder 1 60 folds transversely at the point 2 and has upon the outer face at one end the button 3 and at the other end upon the inner face the snap 4 engaging the button to hold the binder in folded closed position. Upon the inner 65 face of the binder there is secured a pair of members 5 and 6 respectively, setting up the pockets 7 and 8 which pockets open in opposite direction, the pocket 7 opening toward that end of the folder which carries the button 3 and the pocket 8 opening toward the other end of the folder as is shown. 70

Check books which are furnished for folders of the type described have, instead of a full back, a tongue 9 secured at the head 75 of the book and the free end of this tongue is adapted to slip into the pocket 8 of the holder to thus position the book properly therein.

After the check book has once been folded, 80 the free ends of the leaves thereof will, when the book is opened out for use, close up and to prevent this annoyance there has been provided the clip member indicated generally by the numeral 10 which is adapted to 85 hold down the free ends of the leaves at all times.

This clip member comprises a relatively long flat body of a material 11 which extends transversely of the folder through the 90 pocket 7 and the ends of this member extend through the inner side of the pocket as is clearly shown in Figure 3 where they are bent upwardly and inwardly as indicated at 12 providing the inturned hooked ends as 95 shown. Beneath these hooked ends 12 of the clip member 10, the side edges of the check book are positioned, at the free end of the book as shown in Figure 1. Thus it will be seen that when the folder or binder 1 is 100 opened out in the manner shown in Figure 1, the free ends of the leaves of the check book will be prevented from closing due to the inturned ends 12 of the member 10 which are engaged over the edges thereof. 105

From the foregoing description it will be readily seen that there has been provided a new and novel means for overcoming the annoying tendency of folding check book leaves to close while one is writing a check, 110

thus saving time and the smearing and ruination of a number of checks before one is properly written.

Having thus described my invention what 5 I claim is:—

1. A folding pad holder of the character set forth, comprising, in combination with a folding back, a means carried by said back for engaging the side edges of a pad held 10 therein to hold the free ends of the leaves thereof in position against the inner face of the back.
2. A folding pad holder of the character set forth, comprising, in combination with 15 a folding back, a holding member secured to said back and having hooked means for

engaging over the edges of the free ends of the leaves of a pad, normally encased by the back.

3. A folding pad holder of the character 20 set forth, comprising, in combination with a folding back, a holding member comprising a flat strip of material secured transversely of the back adjacent one end thereof and having its ends extending beyond the inner face of the back and inturned to provide hooks adapted to engage over the side edges of the free ends of a pad, held by the back.

In testimony whereof, I affix my signature 25 hereto.

HARRY P. HENOCH.
